United States Patent

Des. 240,245
Patented June 8, 1976

240,245

GOLF PUTTER

Louis Aragona, 11 Scheiber Terrace
Cedar Grove, N.J. 07009

Filed May 20, 1974, Ser. No. 471,245

Term of patent 14 years

Int. Cl. D21—02

U.S. Cl. D34—5 GH

FIG. 5

FIG. 1 is a front elevation of my new golf putter design.

FIG. 2 is a right side elevation of my new golf putter design.

FIG. 3 is a left side elevation of my new golf putter design.

FIG. 4 is a rear elevation of my new golf putter design.

FIG. 5 is a perspective of the head of my new golf putter design.

The top of the putter head is plain.

I claim:

The ornamental design for a golf putter, as shown and described.
